UNITED STATES PATENT OFFICE

ROBERT W. HULL, OF HINGHAM, AND WILLIAM J. MACDONALD, OF WATERTOWN,
MASSACHUSETTS; SAID MACDONALD ASSIGNEE TO SAID HULL

VENDING MACHINE

Application filed July 23, 1928. Serial No. 294,634.

Our present invention relates to vending machines, and more particularly to machines adapted to vend or dispense articles from columns or stacks after insertion, in the machine, of a suitable or proper coin.

5 An important object of the present invention is to construct a machine with a minimum number of moving, reciprocating, or operating parts, and to eliminate the large number 10 of springs heretofore utilized in vending or dispensing machines. We prefer utilizing only a single spring in our novel machine, and in fact we can dispense with even this one spring, if desired.

15 Another object of the invention is the provision of a machine containing a plurality of columns of articles to be dispensed, and to provide, externally of the machine, a single operating handle, by means of which single 20 handle articles from any predetermined number of columns can be simultaneously discharged from the machine. This is an important feature from many standpoints, in that it simplifies the manufacture and construction of the machine, and also greatly 25 simplifies the operation of the machine. Thus if a purchaser desires to secure several articles from our machine, he will predetermine from what columns he wishes said articles, and by insertion of the proper number 30 of coins, in their proper locations, he may then, by a single operation of the single operating handle, secure all of the articles desired simultaneously.

35 Another object of the invention is the provision of novel means whereby columns of different width may be utilized in the same machine, to accomodate articles of different sizes, thus affording the purchaser a wide 40 range of choice or selection from a single machine.

A further object of the invention resides in the provision of novel means to prevent discharge of articles from the machine when 45 a coin of smaller dimensions than that intended is utilized.

Another feature of our novel machine resides in the provision of novel means, automatically operable, to return a coin to a prospective purchaser if the particular column

from which said purchaser wishes an article is empty.

A still further feature of the invention consists in the fact that all of the columns in our novel machine are removable. Thus said 55 columns may be loaded while in the machine, or they may be removed from the machine for loading outside thereof.

Another and important feature of novelty in our machine resides in the fact that we are 60 enabled, in a compact machine, to provide a larger number of columns of articles than has heretofore been deemed possible. This important feature is made possible by the arrangement of columns within our machine, 65 wherein a plurality of rows of vertical columns or magazines arranged side by side, extend longitudinally of the machine.

A further object of the invention is to provide coin chutes or mechanisms leading to 70 each of said columns, these coin chutes being inclined, and arranged one above the other. On the front of the machine is a suitable display portion, indicating the articles contained by the individual columns, and the 75 coin entrances are so located with relation to this display portion that a purchaser can instantly determine into which coin entrance a coin must be inserted in order to obtain therefrom a desired article.

80 Another object of the invention resides in the provision of a simple rack and gear mechanism, operated by the single handle above mentioned.

85 Another feature of the invention resides in the provision of means to compel complete operation of the machine in one direction before it can be returned to normal position, this last mentioned means comprising a two-way pawl associated with one of the above 90 mentioned racks, said pawl cooperating with a suitable ratchet preferably formed in one of the rack guiding tracks or walls.

In carrying out our present invention, we provide, in a suitable cabinet or casing, a 95 pair of movable racks, each having a predetermined range or length of movement or travel. Meshing with these racks are a pair of gears, fixed to a shaft extending outside of said casing. A single operating handle is 100

affixed to the outer end of said shaft, rotation of said handle in turn rotating said gears and moving said racks longitudinally of the machine.

5 Affixed to said racks, at predetermined intervals, are trays, each tray having a plurality of coin receiving recesses therein. Slidably mounted in suitable tracks, over each of said trays, are a plurality of pusher

10 members or ejectors, each ejector having a coin receiving slot or channel therein. Located over each of said ejectors is a column or magazine adapted to receive a column or stack of articles. Movement of the racks by

15 said operating handle will also move all of said trays in the same direction as the direction of travel of said racks. When it is desired to secure an article from one of said magazines, a suitable coin, such as a nickel, is

20 inserted in the proper coin entrance, and after passing through the chute, said coin will come to rest in the groove in said ejector and also in the cooperating coin receiving recesses in the movable tray.

25 Now, on movement of the racks and trays, the ejector which is engaged by the nickel will also move in the same direction as the trays and racks, and will cause the discharge of the desired article from its column. As

30 the trays travel along their paths, the coin recesses therein are alined with cooperating slots in fixed plates under said trays, and on reaching a predetermined position the article will have been entirely removed from the

35 column, and the nickel will drop through the slot in said fixed plate, whence it will travel, through a suitable chute, to a locked coin receptacle. On release of the handle, after the trays and racks have reached the limit of

40 their travel, we provide a single spring, which will automatically cause the return of all the racks, trays, and ejector, to normal position. In place of the spring, we may utilize a weight to effect the return of

45 said elements, if desired.

Should a purchaser desire to secure more than one article from said machine, he may insert a coin in as many different coin entrances as he desires. Thereupon, movement

50 of the trays will move all of the ejectors which have been engaged by nickels, and will remove an article from each column controlled by said coin-engaged ejectors. On return of the trays and ejectors to normal po-

55 sition, the articles removed from the columns or stacks will be discharged into a suitable trough at the front of the machine, where they will be readily accessible to the purchaser, all of the coins having meanwhile

60 traveled through the chutes in the fixed plates above mentioned and been deposited in the coin receptacle.

Columns for articles of any width or length may be provided, within reasonable

65 ranges of size, of course, each of these col-

umns, regardless of its width or length, being provided with means to secure it in place in the machine.

The movement of the ejectors and movable trays will, of course, always be uniform, 70 and when columns of varying sizes are utilized, such columns will be spaced nearer to or further from the ejectors as occasion may require.

Should a person endeavor to operate our 75 novel machine with a smaller coin than that intended for said machine, we have provided novel means whereby said coin will be returned to the purchaser, or if the smaller coin should by any chance lodge in the ejector and movable tray, movement of the tray would carry the coin with said tray, but would not operate the ejector.

When the stack of articles from any column 80 is exhausted, we have provided a pivoted arm, normally held upright by the column of articles, but which arm, after the passage of the last article thereby, will drop, through a suitable aperture in the side of the coin chute, into the path of succeeding coins, 85 deflecting said coins in such manner that they will be returned to the purchaser or operator.

We believe that our machine, as above described, is novel, and have therefore claimed 90 the same broadly in the present application.

The above and other features and objects of the invention, details of construction, combinations of parts, advantages, and operation, will be hereinafter more fully pointed 100 out, described and claimed.

Referring to the drawings, illustrating preferred embodiments of the present invention,

Fig. 1 is a front elevation of our novel 105 machine;

Fig. 2 is a vertical sectional view on the line 2—2 of Fig. 1;

Fig. 3 is a vertical sectional view on the 110 line 3—3 of Fig. 2;

Fig. 4 is a cross-sectional view on the line 4—4 of Fig. 3;

Fig. 5 is a cross-sectional view on the line 5—5 of Fig. 4;

Fig. 6 is a fragmentary detail, on an enlarged scale, of the operating handle, rack and gear, coin chute, ejector, movable tray and fixed plate;

Fig. 7 is a fragmentary front view, partly broken away, of the rack and gear mechanism, and the two-way pawl and ratchet device;

Fig. 8 is a vertical sectional view, on an enlarged scale, on the line 8—8 of Fig. 2;

Fig. 9 is a vertical sectional view on the 125 line 9—9 of Fig. 8;

Fig. 10 is a view corresponding to Fig. 8, but illustrating the ejector after having removed the lowermost article from the column;

Fig. 11 is a perspective view of the pusher member or ejector;

Fig. 12 is a perspective view of one of the movable trays located over a fixed plate, and the spring means to automatically return said trays to normal position;

Fig. 13 is a perspective view of one of the magazines;

Fig. 14 is a cross-sectional view on the line 10 14—14 of Fig. 2; and

Fig. 15 is a cross-sectional view on the line 15—15 of Fig. 1.

Referring now to the drawings for a particular description of the invention, its construction, assembly and operation, our novel machine comprises frame members 1 secured to which are side, top, bottom and cross frames, angles or strips 1a, and removably mounted in the front of this frame is a plate 2 having thereon a display portion or cabinet 3 within which are mounted a plurality of articles 4 to indicate to purchasers the contents of the machine. These articles are protected by removable transparent panels 5, and are held in position by tacks or pointed members 6 which penetrate through the plate 2. The cabinet 3 has coin entrances 7 positioned beside each of the articles, the purchaser depositing his coin, such as a nickel, in the coin entrance adjacent to the article which he desires to purchase.

Above the plate 2 is another removable plate 8, and below the plate 2 is a plate 9a, which may be fixed or removable, as desired, although preferably being fixed.

If it should be desired, at any time, to rearrange the articles within the display case 3, the plate 8 may be readily removed, following which the plate 2 carrying the case 3 may be removed, the glass panels taken out, and any desired arrangement made of the articles within the casing.

The plate 8 has thereon a flange or protecting strip 9 to cover and protect the top of the casing 3, there being suitable interlocking lugs on the casing, as clearly shown at 10 in Fig. 2.

The top or cover 11 is provided, having 50 lugs 11a adapted to catch under one of the frames 1, and I provide a suitable locking bolt 12 engaging in a cam 13. Release of the locking bolt 12 permits the cam 13 to be rotated, by means of the knob 14, thus withdrawing the bolts 15, 15, 15 from under the frame members 1 and permitting the top to be raised.

Guides 16 for the bolts or rods 15 are provided, one end of each rod 15 being pivotally secured to the cam 13.

Secured to certain of the frame members 1 are upright L-members 17 arranged at predetermined intervals throughout the length of the machine, and adjacent to the tops of these L-members are affixed cross-bars 18

having notches 19 therein at predetermined intervals.

We utilize a plurality of magazines, illustrated in Fig. 13, each of these magazines comprising a pair of channel members 20 united at their upper ends by a bar 21, said bar having a bent portion 22 and from this bent portion depends an ear 23 having thereon a lug 24 adapted to seat in the notch or recess 19 in the cross-bar 18. This secures 75 the magazine in position at the upper end. At their lower ends the channel members 20 are united by a bar or brace 25. In order to secure the magazines in position at their bottoms, in the machine, we provide, on each 80 magazine, a pair of flanges 26 having apertures 27 therein. Running longitudinally of the machine are a plurality of tracks or rails 28, and on these rails, at predetermined intervals, are pins 29, over which the apertures 27 in the flanges 26 will fit. These flanges will be of the same length, regardless of the size of the magazine, and thus we are enabled to position, in our novel machine, a wide range 85 of sizes of magazines, to carry a wide range 90 of sizes of articles. Fig. 4 illustrates some of the magazines in position, and also the space or positions for other magazines, but a glance at Fig. 4 will indicate the variation in size of the magazines utilized. For example, 95 the magazine indicated at 30 is much shorter and narrower than the magazine indicated at 31.

These magazines are adapted and intended to carry articles indicated at 32, 32, these articles being of different sizes, shapes and contours.

Under each magazine is slidably mounted an ejector 33 having a face 34 adapted to engage one edge of the lowermost article in each column or stack. Each ejector has a plate 35, of greater width than the ejector, the extending edges of said plate riding in grooves 36 in the rails 28, and the ejectors being guided thereby. The ejector 33 also has an aperture 37 therethrough, through which a suitable coin is adapted to pass.

The aperture 37 is adapted to be aligned, when the ejector 33 is in normal position, as illustrated in Fig. 8, with an aperture 38 in a sliding tray 39. Each of these trays extends the full width of the machine and are secured at their ends to racks 40. As illustrated in the drawings, our novel machine is constructed to accommodate twelve magazines, although it will be readily understood that this is optional, and that we may construct our machines to accommodate or carry as many magazines as desirable. Each tray 39, therefore, extends under three magazines, and each tray will have three apertures 38 therein, aligned with each of the apertures 37 in the three ejectors 33 in that line. Beneath each tray 39 is a fixed plate 41 secured to a rib or wall 42, this rib 42 and the rib or wall 43 serv-

ing as guides for the racks 40 in their longitudinal travel. The racks 40, there being one of these racks at front and back of the machine, as will be understood, run on tracks or supports 44. When a coin, such as a nickel, 5 has been inserted through one of the entrances 7, it will come to rest partly in the aperture 37, and will extend through the aperture 39 and will rest on the plate 41, having engagement with each of the ejectors 33 and 10 tray 39.

Movement is imparted to the racks 40 by means of a pair of gears 45 mounted on a shaft 46 extending from the front to the back of the machine. A portion of this shaft 15 46 projects beyond the front of the machine and has therein a handle 47. The gears 45 mesh with the teeth 48 on the racks 40. Rotation of the handle 47 to the right, or in a clockwise direction, as viewed in Figs. 1 and 20 7, will cause a rotation of the gears which will in turn impart longitudinal movement or travel to the racks 40 to the right. The racks 40 will, of course, carry with them the trays 39, which are affixed to said racks. 25

Assuming a nickel, indicated at 49, to be positioned in one of the ejectors 33, it will be readily seen that movement of the tray to the right will cause the ejector 33 to also move to the right, see Figs. 8 and 10. As the 30 ejectors 33 move to the right, the face 34 thereof will engage the lowermost article of the stack, here illustrated as 50, and will separate said article from the stack and move it transversely thereof. When the racks have completed the limit of their movement, the article 50 will be in the position illustrated in Fig. 10, resting on the plate 35, while the ejector 33 is acting as a support for the remainder of the stack. At the same time the 35 nickel will have come into alignment with a chute 52 depending from the plate 41, and will drop thereinto. The nickel will then be deposited in a suitable coin receptacle, as indicated at 53, the chutes 52 being inclined toward said receptacle, and said receptacle being inclined to the left, as viewed in Fig. 3. Access to this coin receptacle may be had through the side of the machine.

The racks 40, trays 39 and ejectors 33 are now at their extreme limit of movement to the right, the stop 54 having stopped the ejector, and the racks being limited by the extent of the teeth thereon.

In order to automatically return said racks, 40 trays, and ejectors to normal position, after release of the handle 47, we provide a spring 55 fixed to an eye 56 at the top of the machine, and fixed at its lower end to a flexible element 57, such as a cord. Said cord 57 runs over a pulley 58 mounted in a bracket 59 on the plate 41 which is nearest to the left of the machine. The cord 57 is then affixed to the tray 39 which is immediately above the last mentioned plate 41. On release of the handle 55

47, therefore, the tension of the spring 55 will pull on said tray, and will return said tray, as well as the racks 40 to which it is secured, and the other trays, to normal position. Each ejector has a depending edge 60 engaged by the tray 39, and the ejectors which have been moved will also thus be automatically returned to normal position. 70

As the ejector 33 moves to normal position, the article 50 will strike against the next 75 succeeding article 61, which will have descended to a position on top of the ejector 33, and upon travel of the plate 35 to its normal position, the article 50 will be tumbled off, and will descend, through a large chute 62, 80 into a trough 63 at the front of the machine, an opening 64 being provided immediately above this trough to permit the operator or purchaser to obtain the articles discharged 85 from the machine.

As the plate 35 is returned to normal position, the article 61 will drop onto said plate, said plate thus serving as a support for the stack until the operation is repeated. The walls of the channels 20 are cut away, at the 90 bottom, as indicated at 65, to permit the passage of the lowermost article thereunder.

To prevent upward movement of the racks 40 during their travel, guides 66 are provided.

It is desirable that each operation of the 95 machine shall be completed, and for this purpose we provide, on the front rack 40, a pivoted two-way pawl 67 adapted to engage a ratchet 68 formed on the top of the guide rail 43. Once the pawl has engaged this 100 ratchet, movement of the racks 40 to the right must be completed, or the pawl will hold the machine in the position to which it has been moved. Once cleared of the ratchet, however, after completion of the operation, 105 the pawl will drag, with the rack 40, back to normal position.

In order to insure operation of the machine by the proper coins, we provide a plurality of coin mechanisms 69, each having therein a 110 plurality of coin chutes 70, 70, 70. Each of these mechanisms 69 is arranged at the rear of each set of magazines, each chute 70 being aligned with a coin entrance 7. When a coin of the proper size is inserted through a pre-determined entrance 7, it will travel through the corresponding chute 70, and strike against a pin 71, which will deflect said coin into the aperture 37 in the ejector 33. If a smaller coin than intended is utilized, however, it 115 will not strike the pin 71, but will travel on through the chute, and will be carried through an inclined aperture 72 and returned to the purchaser by means of the chute 62. If, by any chance, a smaller coin should 120 strike the pin 71 and be deflected into the apertures in the ejector 33 and tray 39, and the handle 47 were operated, the tray 39 would move forwardly, carrying the coin, but said coin would travel through an arcuate 125 130

groove 73 formed in the under part of the ejector 33. Thereupon it would drop into the chute 52 and from thence to the coin mechanism. This action is clearly illustrated 5 in Fig. 9, where the smaller coin, indicated at 74, is illustrated as of smaller dimensions than the groove 73, thus permitting the passage of the coin under the ejector 33 without operating the same. The pin 75 will also 10 assist in guiding coins into the apertures 37 and 38.

In order to prevent loss of a coin to a purchaser after a magazine is empty, we provide the novel mechanism now to be described.

15 On the shaft 80 adjacent to the bottom of each magazine is pivoted an arm 81. The lower end 82 of this arm is engaged by the articles in the magazine, and the arm 81 is therefore held in a vertical position, as illustrated 20 in Fig. 8. Upon the discharge of the last article from a magazine, however, the arm 81, because of its weight, will drop, and will enter a slot 83 in the wall of the chute 70, as illustrated in dotted lines 25 in Fig. 10 and in full lines in Fig. 6. When in this position, the arm 81 will be directly above the aperture 37 in the ejector 33. A coin inserted when the arm 81 is in this position, will strike the arm 81, and be deflected 30 by said arm, as well as by the pin 75, into the aperture or channel 72, and thence returned, by way of the chute 62, to the purchaser. On refilling an empty magazine, the weight of the articles inserted therein will remove the 35 arm 81 from the path of the coin, and again permit successful operation of the machine.

Spacing washers 84 are utilized to retain the walls of the coin chutes 70 a predetermined distance apart.

40 The operation of our novel machine is simple in the extreme, and will be readily understood by those skilled in the art, being briefly described as follows:

A purchaser inserts, through one or more 45 of the coin entrances 7 a coin, or coins, for example, a nickel. He may, if desired, insert a coin in every entrance. These coins will follow or travel through the chutes 70, and will come to rest in the aperture 37 in the ejectors 33, and in the aperture 38 in the trays 39, resting on the fixed plates 41.

Rotation of the handle 47 in the proper direction will cause the gears 45 to move the racks 40 to the right, carrying with said racks 50 the trays 39, and, through the medium of the coins, certain of the ejectors 33. The face 34 of each ejector in which a coin has been positioned, will engage the lowermost article of the column, said article resting on the plate 55. Continued movement will separate this lowermost article from the stack and move it forwardly, the next-to-the-lowermost article dropping onto the ejector 33 after the lowermost article has passed from the magazine. Upon cessation of movement, and re-

lease of the handle, the spring 55 will retract the trays 39 and racks 40, and also, because of the bottom projections 60, the ejectors 33 which have been moved. The coins will, of course, have passed through the chutes leading from the plates 41 to the coin receptacle. As the ejectors are retracted, the article which has been separated from the stack will strike the article which is now resting on the ejector, and as the plate 35 is withdrawn from under said article, it will drop or tumble from the plate 35, and descend, by way of the chute 62, to the trough 63. It will be understood that all of the articles desired, and for which coins have been inserted in the machine, will drop simultaneously, thus greatly expediting the speed of operation, and simplifying the machine to a great degree. Upon emptying of any magazine, the arm 31 will operate to prevent operation of the machine by a coin inserted for that particular magazine, and said coin will be returned to the purchaser in the manner above described. Thus the purchaser is insured against loss of his coin when the magazine from which he desires an article is empty.

This feature of being enabled to secure any desired number of articles simultaneously, and by only one operation of the machine, will appeal to those skilled in the art as well as to the general public.

While we have necessarily described our present invention somewhat in detail, it will be appreciated that we may vary the size, shape and arrangement of parts within reasonably wide limits, without departing from the spirit of the invention. We may also, as will be readily understood, construct our novel machine with any desired number of magazines, and it will be apparent that we are enabled to accommodate, in a compact machine, a larger number of magazines than in prior machines of this type.

Our invention is further described and defined in the form of claims as follows:

1. In a vending machine, a column of articles, an ejector located at one side of the lowermost article and having a coin receiving recess therein, a portion of said ejector extending under and supporting said column, a tray slidably mounted beneath said ejector and having a coin receiving recess alined with the recess in said ejector, means to move said tray and said ejector transversely of said column, and means operated by ejection of the last article from said column, to prevent reception of a coin in the coin receiving recess of said ejector.

2. In a vending machine, a column of articles, an ejector located at one side of the lowermost article, a tray slidably mounted beneath said ejector, means to move said tray and said ejector transversely of said column, and means operated by ejection of the last article from said column, to prevent

reception of a coin in the coin receiving recess of said ejector.

3. In a vending machine, a column of articles, an ejector located at one side of the lowermost article and having a coin receiving recess therein, a tray mounted beneath said ejector and having a coin receiving recess alined with the recess in said ejector, means to move said tray transversely of said column, said ejector being inoperative unless a coin is positioned in said recesses, and means operated by ejection of the last article from said column, to prevent reception of a coin in the coin receiving recess of said ejector.

4. In a vending machine, a plurality of columns of articles, an ejector located at one side of the lowermost article in each column and having a coin receiving recess therein, a movable tray normally positioned under each of said columns and having a coin receiving recess alined with the recess in a corresponding ejector, and means to move said trays transversely of said columns, only those ejectors in which coins have been received moving with the trays.

5. In a vending machine, a plurality of columns of articles, an ejector located at one side of the lowermost article in each column and having a coin receiving recess therein, a movable tray normally positioned under each of said columns and having a coin receiving recess alined with the recess in a corresponding ejector, means to move said trays transversely of said columns, only those ejectors in which coins have been received moving with the trays to eject articles from their respective columns, and means to limit the travel of said ejectors.

6. In a vending machine, a plurality of columns of articles, an ejector located at one side of the lowermost article in each column and having a coin receiving recess therein, a movable tray normally positioned under each of said columns and having a coin receiving recess alined with the recess in a corresponding ejector, means to move said trays transversely of said columns, only those ejectors in which coins have been received moving with the trays to eject articles from their respective columns, means to limit the travel of said ejectors, and means to automatically return said trays and said ejectors to normal position.

7. In a vending machine, a plurality of columns of articles, an ejector located at one side of the lowermost article in each column and having a coin receiving recess therein, a movable tray normally positioned under each of said columns and having a coin receiving recess alined with the recess in a corresponding ejector, means to move said trays transversely of said columns, only those ejectors in which coins have been received moving with the trays, a fixed plate under each

of said trays and having a slot therein, said coins, at a predetermined position during the travel of said ejectors and trays, entering said slots, and a receptacle in which said coins are deposited.

8. In a vending machine, a plurality of columns of articles, an ejector located at one side of the lowermost article in each column and having a coin receiving recess therein, a movable tray normally positioned under each of said columns and having a coin receiving recess alined with the recess in a corresponding ejector, means to move said trays transversely of said columns, only those ejectors in which coins have been received moving with the trays, and means operated by ejection of the last article from a column, to prevent reception of a coin in the coin receiving recess of the ejector which operates on that column.

9. In a vending machine, an ejector having a coin receiving aperture therein, a tray beneath said ejector, said tray having a coin receiving recess normally alined with the aperture in said ejector, said ejector also having an arcuate groove on its under surface whereby coins of smaller dimensions than intended to operate said ejector will travel with said tray under said ejector without moving the same.

10. In a vending machine, a rack on each side thereof, a gear engaging each of said racks, a shaft on which said gears are mounted, a handle on the outer end of said shaft, a plurality of trays affixed to said racks, each tray having a coin receiving recess therein, rotation of said handle effecting movement of said racks and said trays longitudinally of the machine, a column of articles above each tray, an ejector at one side of the lowermost article in each column and having a coin receiving aperture therein, and means to admit a coin to the aperture in each of said ejectors and its cooperating recess in said tray, movement of said trays causing movement of such ejectors as have coins therein to eject the lowermost article from each of the columns controlled by said last named ejectors.

11. In a vending machine, a rack on each side thereof, a gear engaging each of said racks, a shaft on which said gears are mounted, a handle on the outer end of said shaft, a plurality of trays affixed to said racks, each tray having a coin receiving recess therein, rotation of said handle effecting movement of said racks and said trays longitudinally of the machine, a column of articles above each tray, an ejector at one side of the lowermost article in each column and having a coin receiving aperture therein, means to admit a coin to the aperture in each of said ejectors and its cooperating recess in said tray, movement of said trays causing movement of such ejectors as have coins therein to eject the low-

ermost article from each of the columns controlled by said last named ejectors, a fixed plate under each of said trays each having a slot therein, a coin receptacle, and chutes leading from said slots to said receptacle, said coins, at a predetermined position during the travel of said ejectors and trays dropping through said slots.

12. In a vending machine, a rack on each side thereof, a gear engaging each of said racks, a shaft on which said gears are mounted, a handle on the outer end of said shaft, a plurality of trays affixed to said racks, each tray having a coin receiving recess therein, rotation of said handle effecting movement of said racks and said trays longitudinally of the machine, a column of articles above each tray, an ejector at one side of the lowermost article in each column and having a coin receiving aperture therein, means to admit a coin to the aperture in each of said ejectors and its cooperating recess in said tray, movement of said trays causing movement of such ejectors as have coins therein to eject the lowermost article from each of the columns controlled by said last named ejectors, and means to automatically return said ejectors and trays to normal position.

13. In a vending machine, a rack on each side thereof, a gear engaging each of said racks, a shaft on which said gears are mounted, a handle on the outer end of said shaft, a plurality of trays affixed to said racks, each tray having a coin receiving recess therein, rotation of said handle effecting movement of said racks and said trays longitudinally of the machine, a column of articles above each tray, an ejector at one side of the lowermost article in each column and having a coin receiving aperture therein, means to admit a coin to the aperture in each of said ejectors and its cooperating recess in said tray, movement of said trays causing movement of such ejectors as have coins therein to eject the lowermost article from each of the columns controlled by said last named ejectors, and means to limit the travel of said ejectors.

14. In a vending machine, a rack on each side thereof, a gear engaging each of said racks, a shaft on which said gears are mounted, a handle on the outer end of said shaft, a plurality of trays affixed to said racks, each tray having a coin receiving recess therein, rotation of said handle effecting movement of said racks and said trays longitudinally of the machine, a column of articles above each tray, an ejector at one side of the lowermost article in each column and having a coin receiving aperture therein, means to admit a coin to the aperture in each of said ejectors and its cooperating recess in said tray, movement of said trays causing movement of such ejectors as have coins therein to eject the lowermost article from each of the columns controlled by said last named ejectors, and means to limit the travel of said ejectors.

trolled by said last named ejectors, and means to guide said ejectors during their travel.

15. In a vending machine, a rack on each side thereof, a gear engaging each of said racks, a shaft on which said gears are mounted, a handle on the outer end of said shaft, a plurality of trays affixed to said racks each tray having a coin receiving recess therein rotation of said handle effecting movement of said racks and said trays longitudinally of the machine, a column of articles above each tray, an ejector at one side of the lowermost article in each column and having a coin receiving aperture therein, means to admit a coin to the aperture in each of said ejectors and its cooperating recess in said tray, movement of said trays causing movement of such ejectors as have coins therein to eject the lowermost article from each of the columns controlled by said last named ejectors, means to support said racks, and means to guide said racks during their longitudinal movement.

16. In a vending machine, a plurality of columns of articles, an ejector located at one side of the lowermost article in each column and having a coin receiving recess therein, a movable tray normally positioned under each of said columns and having a coin receiving recess alined with the recess in a corresponding ejector, and means to simultaneously move all of said trays transversely of said columns, only those ejectors in which coins have been received moving with the trays.

17. In a vending machine, a plurality of columns of articles, an ejector located at one side of the lowermost article in each column and having a coin receiving recess therein, a movable tray normally positioned under each of said columns and having a coin receiving recess alined with the recess in a corresponding ejector, and a single operating handle to simultaneously move all of said trays transversely of said columns, only those ejectors in which coins have been received moving with the trays.

18. In a vending machine, a rack on each side thereof, a gear engaging each of said racks, a shaft on which said gears are mounted, a handle on the outer end of said shaft, a plurality of trays affixed to said racks, each tray having a coin receiving recess therein, rotation of said handle effecting movement of said racks and said trays longitudinally of the machine, a column of articles above each tray, an ejector at one side of the lowermost article in each column and having a coin receiving aperture therein, means to admit a coin to the aperture in each of said ejectors and its cooperating recess in said tray, movement of said trays causing movement of such ejectors as have coins therein to eject the lowermost article from each of the columns controlled by said last named ejectors, means to guide said ejectors during their travel, and means to limit the travel of said ejectors.

19. In a vending machine, a rack on each side thereof, a gear engaging each of said racks, a shaft on which said gears are mounted, a handle on the outer end of said shaft, a plurality of trays affixed to said racks, each tray having a coin receiving recess therein, rotation of said handle effecting movement of said racks and said trays longitudinally of the machine, a column of articles above each tray, an ejector at one side of the lowermost article in each column and having a coin receiving aperture therein, means to admit a coin to the aperture in each of said ejectors and its cooperating recess in said tray, movement of said trays causing movement of such ejectors as have coins therein to eject the lowermost article from each of the columns controlled by said last named ejectors, a fixed plate under each of said trays, each having a slot therein, a coin receptacle, chutes leading from said slots to said receptacle, said coins, at a predetermined position during the travel of said ejectors and trays dropping through said slots, and means operated by ejection of the last article from a column to prevent reception of a coin in the coin receiving recess of the ejector which operates on said column. 70
20. In a vending machine, a column of articles, an ejector located at one side of the lowermost article and having a coin receiving recess therein, a portion of said ejector extending under and supporting said column, a tray slidably mounted beneath said ejector and having a coin receiving recess alined with the recess in said ejector, means to move said tray and said ejector transversely of said column, and means operated by ejection of the last article from said column, to automatically eject subsequently inserted coins from said machine. 80
21. In a vending machine, a rack on each side thereof, a gear engaging each of said racks, a shaft on which said gears are mounted, a handle on the outer end of said shaft, a plurality of trays affixed to said racks, each tray having a coin receiving recess therein, rotation of said handle effecting movement of said racks and said trays longitudinally of the machine, a column of articles above each tray, an ejector at one side of the lowermost article in each column and having a coin receiving aperture therein, means to admit a coin to the aperture in each of said ejectors and its cooperating recess in said tray, movement of said trays causing movement of such ejectors as have coins therein to eject the lowermost article from each of the columns controlled by said last named ejectors, a fixed plate under each of said trays, each having a slot therein, a coin receptacle, chutes leading from said slots to said receptacle, said coins, at a predetermined position during the travel of said ejectors and trays dropping through said slots, and a pivoted arm adjacent to each of said chutes, each of said arms being released by the ejection of the last article from a column, whereby said arm projects into its adjacent chute to prevent reception of a coin in the coin receiving recess of the ejector which operates on that column. 90
22. In a vending machine, a plurality of columns of articles, an ejector located at one side of the lowermost article in each column and having a coin receiving recess therein, a movable tray normally positioned under each of said columns and having a coin receiving recess alined with the recess in a corresponding ejector, means to move said trays transversely of said columns, only those ejectors in which coins have been received moving with the trays, and a pivoted lever operated by ejection of the last article from a column to project into the path of a coin to prevent 100
23. In a vending machine, a rack on each side thereof, a gear engaging each of said racks, a shaft on which said gears are mounted, a handle on the outer end of said shaft, a plurality of trays affixed to said racks, each tray having a coin receiving recess therein, rotation of said handle effecting movement of said racks and said trays longitudinally of the machine, a column of articles above each tray, an ejector at one side of the lowermost article in each column and having a coin receiving aperture therein, means to admit a coin to the aperture in each of said ejectors and its cooperating recess in said tray, movement of said trays causing movement of such ejectors as have coins therein to eject the lowermost article from each of the columns controlled by said last named ejectors, a fixed plate under each of said trays, each having a slot therein, a coin receptacle, chutes leading from said slots to said receptacle, said coins, at a predetermined position during the travel of said ejectors and trays dropping through said slots, and means operated by ejection of the last article from a column to prevent reception of a coin in the coin receiving recess of the ejector which operates on said column. 110
24. In a vending machine, a plurality of columns of articles, an ejector located at one side of the lowermost article in each column and having a coin receiving recess therein, a movable tray normally positioned under each of said columns and having a coin receiving recess alined with the recess in a corresponding ejector, means to move said trays transversely of said columns, only those ejectors in which coins have been received moving with the trays, and a pivoted lever operated by ejection of the last article from a column to project into the path of a coin to prevent 120
25. In a vending machine, a rack on each side thereof, a gear engaging each of said racks, a shaft on which said gears are mounted, a handle on the outer end of said shaft, a plurality of trays affixed to said racks, each tray having a coin receiving recess therein, rotation of said handle effecting movement of said racks and said trays longitudinally of the machine, a column of articles above each tray, an ejector at one side of the lowermost article in each column and having a coin receiving aperture therein, means to admit a coin to the aperture in each of said ejectors and its cooperating recess in said tray, movement of said trays causing movement of such ejectors as have coins therein to eject the lowermost article from each of the columns controlled by said last named ejectors, a fixed plate under each of said trays, each having a slot therein, a coin receptacle, chutes leading from said slots to said receptacle, said coins, at a predetermined position during the travel of said ejectors and trays dropping through said slots, and means operated by ejection of the last article from a column to prevent reception of a coin in the coin receiving recess of the ejector which operates on said column. 130

reception of a coin in the coin receiving recess of the ejector which operates on that column.

25. In a vending machine, a column of articles, an ejector located at one side of the lowermost article and having a coin receiving recess therein, a portion of said ejector extending under and supporting said column, a tray slidably mounted beneath said ejector and having a coin receiving recess alined with the recess in said ejector, means to move said tray and said ejector transversely of said column, and a pivoted lever operated by ejection of the last article from a column to project into the path of a coin to prevent reception of a coin in the coin receiving recess of the ejector which operates on that column.

26. In a vending machine, a plurality of columns of articles, an ejector located at one side of the lowermost article in each column and having a coin receiving recess therein, a movable tray normally positioned under each of said columns and having a coin receiving recess alined with the recess in a corresponding ejector, means to move said trays as a unit transversely of said columns, only those ejectors in which coins have been received moving with the trays to eject articles from their respective columns, and means to limit the travel of said ejectors.

30 27. In a vending machine, a plurality of columns of articles, an ejector located at one side of the lowermost articles in each column and having a coin receiving recess therein, a movable tray normally positioned under each of said columns and having a coin receiving recess alined with the recess in a corresponding ejector, means to move said trays as a unit transversely of said columns, only those ejectors in which coins have been received moving with the trays to eject articles from their respective columns, means to limit the travel of said ejectors, and means to automatically return said trays and said ejectors to normal position.

45 28. In a vending machine, a plurality of columns of articles, an ejector located at one side of the lowermost articles in each column and having a coin receiving recess therein, a movable tray normally positioned under each of said columns and having a coin receiving recess alined with the recess in a corresponding ejector, means to move said trays as a unit transversely of said columns, only those ejectors in which coins have been received moving with the trays to eject articles from their respective columns, means to limit the travel of said ejectors, and a single means to automatically return said trays and said ejectors to normal position.

60 29. In a vending machine, a rack on each side thereof, a gear engaging each of said racks, a shaft on which said gears are mounted, a handle on the outer end of said shaft, a plurality of trays affixed to said racks, each tray having a coin receiving recess therein,

rotation of said handle effecting movement of said racks and said trays longitudinally of the machine, a column of articles above each tray, an ejector at one side of the lowermost article in each column and having a coin receiving aperture therein, means to admit a coin to the aperture in each of said ejectors and its cooperating recess in said tray, movement of said trays causing movement of such ejectors as have coins therein to eject the lowermost article from each of the columns controlled by said last named ejectors, a fixed plate under each of said trays, each having a slot therein, a coin receptacle, chutes leading from said slots to said receptacle, said coins, at a predetermined position during the travel of said ejectors and trays dropping through said slots, and a pivoted arm adjacent to each of said chutes, each of said arms being released by the ejection of the last article from a column, whereby said arm projects into its adjacent chute to prevent reception of a coin in the coin receiving recess of the ejector which operates on that column, subsequent deposit of an article in said column automatically returning said arm to normal position.

30 29. In a vending machine, a rack on each side thereof, a gear engaging each of said racks, a shaft on which said gears are mounted, a handle on the outer end of said shaft, a plurality of trays affixed to said racks, each rack having a coin receiving recess therein, rotation of said handle effecting movement of said racks and said trays longitudinally of the machine, a column of articles above each tray, an ejector at one side of the lowermost article in each column and having a coin receiving aperture therein, means to admit a coin to the aperture in each of said ejectors and its cooperating recess in said tray, movement of said trays causing movement of such ejectors as have coins therein to eject the lowermost article from each of the columns controlled by said last named ejectors, means to support said racks, means to guide said racks during their longitudinal movement, and a single means to return said racks to normal position.

31. In a vending machine, a rack on each side thereof, a gear engaging each of said racks, a shaft on which said gears are mounted, a handle on the outer end of said shaft, a plurality of trays affixed to said racks, each rack having a coin receiving recess therein, rotation of said handle effecting movement of said racks and said trays longitudinally of the machine, a column of articles above each tray, an ejector at one side of the lowermost article in each column and having a coin receiving aperture therein, means to admit a coin to the aperture in each of said ejectors and its cooperating recess in said tray, movement of said trays causing movement of such ejectors as have coins therein to

5 eject the lowermost article from each of the columns controlled by said last named ejectors, means to support said racks, means to guide said racks during their longitudinal movement, and a single resilient means to return said racks to normal position.

6 32. In a vending machine, a rack on each side thereof, a gear engaging each of said racks, a shaft on which said gears are mounted, a handle on the outer end of said shaft, a plurality of trays affixed to said racks, each rack having a coin receiving recess therein, rotation of said handle effecting movement of said racks and said trays longitudinally 10 of the machine, a column of articles above each tray, an ejector at one side of the lowermost article in each column and having a coin receiving aperture therein, means to admit a coin to the aperture in each of said ejectors 15 and its cooperating recess in said tray, movement of said trays causing movement of such ejectors as have coins therein to eject the lowermost article from each of the columns controlled by said last named ejectors, means 20 to support said racks, means to guide said racks during their longitudinal movement, and means to return said racks to normal position, return movement of said racks returning said trays and said moved ejectors to 25 30 normal position.

33. In a vending machine, a rack on each side thereof, a gear engaging each of said racks, a shaft on which said gears are mounted, a handle on the outer end of said shaft, a plurality of trays affixed to said racks, each rack having a coin receiving recess therein, rotation of said handle effecting movement of said racks and said trays longitudinally of the machine, a column of articles 35 above each tray, an ejector at one side of the lowermost article in each column and having a coin receiving aperture therein, means to admit a coin to the aperture in each of said ejectors and its cooperating recess in said 40 tray, movement of said trays causing movement of such ejectors as have coins therein to eject the lowermost article from each of the columns controlled by said last named ejectors, means to support said racks, means to 45 50 guide said racks during their longitudinal movement, and means to return said racks and hence said trays to normal position, each of said ejectors having a depending portion engaging one side of its corresponding tray, 55 whereby return of said trays to normal position will automatically return said moved ejectors to normal position.

34. In a vending machine, a plurality of columns of articles, an ejector located at one 60 side of the lowermost article in each column and having a coin receiving recess therein, a movable tray normally positioned under each of said columns and having a coin receiving recess alined with the recess in a corresponding ejector, means to move said trays 65

transversely of said columns, only those ejectors in which coins have been received moving with the trays, and means to compel movement of said trays to ejecting position after initiation of such movement.

70 In testimony whereof, we have signed our names to this specification.

ROBERT W. HULL.
WILLIAM J. MACDONALD.
